UNITED STATES PATENT OFFICE.

MAUDE SIEGEL, OF NEW YORK, N. Y., ASSIGNOR TO FRANKLIN SIMON & CO. INC., OF NEW YORK, N. Y., A CORPORATION OF NEW YORK.

DESIGN FOR A DRESS.

Application filed July 15, 1924. Serial No. 10,156. Term of patent 3½ years.

To all whom it may concern:

Be it known that I, MAUDE SIEGEL, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by the tunic effect of the upper part and by the arrangement of crossing inclined ornamental members with buttons at the point of crossing.

Figure 1 is a perspective view showing the front of a dress, disclosing my new design.

Figure 2 is a rear perspective view of the dress shown in Figure 1.

Figure 3 is an enlarged detail fragmentary plan view showing an enlarged section removed from the front of the dress, illustrating the arrangement of buttons.

I claim:

The ornamental design for a dress, substantially as shown and described.

MAUDE SIEGEL.
